HYDRAULIC MOTOR

George S. Light, Winsted, Conn.

Application November 18, 1937, Serial No. 175,267

8 Claims. (Cl. 121—132)

My invention relates to that class of motors that employ a liquid as a driving medium, and an object of my invention, among others, is the production of a motor of this type comprising a device which constitutes a positive adjustable stop to locate the extreme position of a piston moving in a cylinder in a hydraulic fluid circuit. It is accomplished with a cushioning action at the completion of the motion and with a common fluid inlet and outlet which permits the full force of the hydraulic fluid to be effective upon the surface of the piston, immediately upon the commencement of return motion, thereby permitting quick acceleration of the return motion.

This control opens a new field of endeavor in the design of hydraulic machinery, for it makes possible the use of high speed, rapidly accelerating, reciprocating motion.

Different forms of structures embodying my invention and in the construction and use of which the objects herein set out, as well as others, may be attained, are illustrated in the accompanying drawing in which

Figure 1 is a view in lengthwise central section through the cylinder of a motor embodying my invention.

Figure 2 is a similar view illustrating a modification.

Figure 3 is another similar view illustrating another modification, and

Figure 4 is still another similar view illustrating still another modification.

While my invention is not limited in its application for any particular purpose, it is especially adapted for use in cases where reciprocating movements of mechanical parts are desired. In such cases whenever a piston has been employed for the purpose various means have been used for preventing the piston from delivering blows when it reaches the ends of its paths in its reciprocating movements. My invention has to do with this feature and embodies novel means for preventing the delivery of such blows, this means for accomplishing the purpose being illustrated in the drawing herein in which the numeral 3 denotes a cylinder having a chamber 6, tubes 7 and 8 being attached to opposite ends of the cylinder for delivery and exhaust of fluid thereto and therefrom. It will be understood that any suitable means common to this art and which are frequently employed will be used to control the alternate delivery and exhaust of the liquid to and from each of the tubes. As such means is well understood a showing of it is omitted from the drawings herein. The cylinder

is preferably round in cross-section and is enlarged as at 9 at one end. This enlargement contains an inlet and exhaust chamber 10 which is in communication with the tube 7, as shown in Fig. 1. This end of the cylinder is closed by a plug 11 screw threadedly engaged with the opening into said end. Said plug has an extension 12 projecting past the chamber 10 and into the chamber 6, said extension having a passage 13 between a recess 14 in the extension and the chamber 10. The recess 14 has a flared mouth 15 of frusto-conical shape and opening into the chamber 6.

The opposite end of the cylinder is closed by a plug 16 screw threadedly engaged with an opening into this end of the cylinder. The end of this plug 16 which extends within the cylinder is shaped to form a space 17 between the plug and the cylinder wall with which the tube 8 communicates, in a satisfactory structure and as shown herein, this space constituting an annular chamber. A conical recess 18 is formed in the end of the plug, as shown in Fig. 1 of the drawing.

A piston 19 is located for reciprocating movement in the chamber 6, a piston rod 20 extending from the piston out through the plug 11, said rod being adapted for connection to any member to which reciprocating movement is to be imparted, such member not being shown herein as it is not essential to an understanding of the invention which has to do with the movements of the piston.

The piston is tapered or of conical shape at opposite ends, the end 21 having the rod 20 projecting therefrom and the end 22 being free. The end 21 is shaped to correspond with the shape of the mouth 15 of the recess 14 in the plug 12, and the end 22 is shaped to correspond with the shape of the conical recess in the plug 16.

The plugs 11 and 16 are provided with any suitable means for turning them to adjust their positions in the cylinder and consequently to adjust the positions of the mouth 15 and the recess 18, the angles of which and of the ends 21 and 22 need not be of any particular degree, as various angles of such parts will be found to produce satisfactory results.

In operation liquid being admitted to one end will force the piston to the opposite end of the cylinder and the liquid being exposed to a greater surface-to-volume relationship in the recess 14 and its mouth 15 or in the recess 18, the movement of the piston is stopped without a blow at the end of its path of movement. In this operation a cushion is produced by the greater surface

area that is present in relation to the volume of discharge and also by the greater distance that the final increment of volume must move. When the piston reaches one end of its path of movement the flow of liquid will be reversed, in a manner well understood, and will be admitted through the other tubes 7 or 8 exerting full pressure on the whole surface of the piston from that just described.

In that form of the device shown in Fig. 2 the enlargement on the end of the cylinder is omitted, this cylinder 23 being of the same shape at both ends. The piston is of substantially the same shape as that hereinbefore described. The ends 15 of the plugs 24-25 within the cylinder are shaped to create a space between said ends and the cylinder wall, in a satisfactory form such ends being reduced in size creating projections 26-27 forming annular chambers 28-29 at opposite ends of the cylinder and as shown in Fig. 2. The plugs 24-25 as shown herein are screw threadedly engaged with the openings in the ends of the cylinder, as hereinbefore described, and suitable means for turning the plugs are provided. The tubes 10 7 and 8 communicate with the chambers 28 and 29 and the ends of the piston conform in shape to recesses 30 and 31 in the extensions 26 and 27 respectively. The operation of the piston is substantially the same as that in the device of Fig. 20 1, the cushioning of the piston and the retardation of its movements being effected in the same manner to avoid any hammering noises.

In that form of the device shown in Fig. 3, in which one end only of a cylinder 32 is shown, the plug 33 has a tapered projection 34 which is fitted to a tapered recess 35 in the piston 36. This is a reversal of the shapes of the piston and cylinder ends from that hereinbefore described, but the effects produced are substantially the same as that obtained in the use of the other structures. 40 The tubes for supply and exhaust are arranged substantially as hereinbefore described, one of such tubes 37 only being shown. The opposite end of the piston from that shown has a tapered recess as shown in dotted lines in Fig. 3, the piston rod 20 extending into the center of this recess and this end of the piston and the recess being enough larger than at the opposite end to compensate for the space occupied by the piston rod. 45 The plug 43 will also be correspondingly increased in size to fit the recess in the piston and will have an axial hole to receive the piston rod as shown.

In that form of the device shown in Fig. 4 the end of the piston is reduced in size toward its outer end by a stepped formation 38 on the end of the piston 39, one end of the cylinder only being shown in this view. The plug 40 has a projection 41 with a stepped recess 42. Tubes for supply and exhaust are attached at each end of the cylinder, one of such tubes 37 only being shown. The opposite end of the piston will be correspondingly shaped, the piston being secured to and extending from the axial center as will be understood from an examination of Fig. 3 and the inner end of the plug being formed with a recess to fit the end of the piston and with an axial hole to receive the piston rod as hereinbefore explained.

In all of the structures the cushioning effect and retardation to prevent blows by the piston against the cylinder ends or plugs is obtained, and while light oil or even water may be used as a driving medium to produce satisfactory results, other types of liquid may be employed.

It should be noted that the spaces at the ends

of the chambers in the cylinders are such as to effect pressure of the incoming liquid over the entire surfaces of the ends of the pistons as soon as the latter move away from the chamber ends enough to create any space whatsoever, thereby producing quick acceleration.

It is here remarked that this cushioning effect begins to take place at the instant that the small end or point of the tapered member enters its recess, and this cushioning effect gradually increases in degree until it stops the movement of the piston at the end of its path of movement. The adjustability of the piston ends or plugs is of material advantage in that the length of stroke of the piston and the cushioning effect may be regulated to a nicety.

While the plugs have been shown herein as screw threaded to provide for adjustment of their positions, other constructions may be provided to obtain the results, this adjustment being a very important feature of the invention.

While the ends of the plugs extending into the cylinders are shown as shaped to create annular chambers, I contemplate other forms of the inner ends of the plugs to create other shapes of recesses communicating with the inlet and exhaust tubes.

The motor is primarily designed for unusually rapid reciprocable movements of its piston and especially for obtaining maximum acceleration in the movements of the piston in the start of its reciprocatory movements. To accomplish this result, the coacting faces of the opposite ends of the piston and cylinder walls are so constructed that retardation in movement of the piston is effective substantially at its limit of reciprocatory movement and when moving into contact with the end of the cylinder or abutment therein. Also, it is to be noted that the approaching faces of the piston end and abutment with which the piston comes into direct contact are so angled that when the piston end is in contact with its abutment stop a part of the end of the piston remains in communication with the fluid passage so that the motive fluid is applied to the entire end of the piston at the commencement of movement of the piston away from its abutment stop. The motor has been especially designed for use in connection with a clamp device for the gripping of wires of different diameters. In the reciprocatory movements of the piston, the ends thereof come into direct contact with abutment stops. It is therefore essential that these abutment stops be adjustable to accommodate the use of the motor in connection with a clamp for gripping wires of different diameters. The adjustment of the end abutment 11 in Fig. 1 regulates the reciprocatory movement of the piston in one direction for varying the limit of movement of a movable clamp member toward its cooperative position with a stationary clamp member, while adjustment of the abutment 16 in the other end of the cylinder permits variations in the limits of opening movements of the movable clamp member away from the stationary clamp member to release the wire and guide the discharge thereof.

In accordance with the provisions of the patent statutes I have described the principles of operation of my invention, together with the device which I now consider to represent the best embodiment thereof; but I desire to have it understood that the device shown is only illustrative and that the invention may be carried out by

other means and applied to uses other than those above set out.

I claim:

1. In a hydraulic motor, a cylinder, a piston mounted for reciprocating movement therein, said cylinder having a passage for both inlet and exhaust beyond the limit of reciprocating movement of a part of said piston, an abutment at the end of the cylinder for abutting contact by said piston, the approaching contacting faces of the piston and abutment having surfaces disposed at angles to the longitudinal axis of the cylinder to produce a cushioning effect and a stop to the movement of the piston in one direction whereby full pressure of a motive fluid is applied to a part of the piston when engaged with its abutment stop and to the entire outer end of the piston at the commencement of movement of the piston away from the abutment stop.
2. A hydraulic motor as specified in claim 1, wherein means is provided for adjustably mounting the abutment in the cylinder to vary the length of reciprocatory movement of the piston and the point in the cylinder where the piston comes to rest in contact with the abutment.
3. A hydraulic motor as specified in claim 1, wherein the contacting faces of the piston and abutment comprise a conical projection and a conical recess for the reception of said projection.
4. In a hydraulic motor, a cylinder, a piston mounted for reciprocating movements therein, said cylinder having a passage for both inlet and exhaust adjacent each end thereof beyond the limits of reciprocating movements of a part of the opposite ends of said piston, an abutment at each end of the cylinder respectively for abutting contacts by opposite ends of said piston, the approaching contacting faces of the opposite ends of the piston and abutments having surfaces disposed at angles to the longitudinal axis of the cylinder to produce cushioning effects and stops to the movements of the piston in opposite directions whereby full pressure of a motive fluid is applied to the end of the piston that is engaged with its abutment stop and to the entire outer
- surface of said piston end engaged with said abutment stop at the commencement of movement of the piston away from the abutment stop.
5. A hydraulic motor as specified in claim 4, wherein one of said abutments has an axial bore therein, a rod carried by said piston reciprocably extending through said abutment bore and said abutment bore having a portion thereof annularly enlarged to a chamber axially of the abutment, surrounding the piston rod and in communication with the associated inlet and exhaust passage.
6. A hydraulic motor as specified in claim 4, wherein the inner end of each abutment carries a cylindrical extension terminating respectively inwardly of the adjacent inlet and exhaust passage and of less diameter than the internal diameter of said cylinder to provide an annular chamber surrounding said extension with each chamber and associated inlet and exhaust passage at all times being in communication with a part of the adjacent end of the piston.
7. A hydraulic motor as specified in claim 4 wherein the angularly disposed surfaces of the approaching contacting faces comprise a cylindrical projection on the inner end of each abutment and a terminal conical extension carried by each projection traversing the adjacent inlet and exhaust passage, and the cooperating ends of said piston, each having an annularly reduced projection with a conical recess therein mating with the conical extension on the adjacent abutment end and cooperating therewith to form an annular chamber surrounding the piston and abutment projections when the piston is engaged with an abutment, said chamber being in communication with the adjacent inlet and exhaust passage.
8. A hydraulic motor as specified in claim 4, wherein means is provided for adjustably mounting the abutment blocks in the cylinder to vary the length of reciprocatory movements of the piston and the points in the cylinder where the piston comes to rest in contact with its abutment.
